United States Patent Office

Des. 219,914
Patented Feb. 16, 1971

219,914

WALL FIREPLACE

Edwin L. McElheny, R.R. 1, Nappanee, Ind. 46550

Filed Jan. 15, 1970, Ser. No. 20,939

Term of patent 14 years

Int. Cl. D23—03

U.S. Cl. D23—94

FIG. 1

FIG. 3

FIG. 2

FIG. 1 is a perspective view of a wall fireplace embodying the present design;

FIG. 2 is a front elevational view thereof on a reduced scale; and

FIG. 3 is a side elevational view thereof on a reduced scale.

The top of the wall fireplace is flat.

I claim:

The ornamental design for the wall fireplace, as shown and described.
